UNITED STATES PATENT OFFICE

95,488

DESIGN FOR A SLEEPING GARMENT OR SIMILAR ARTICLE

Louis Davis, Brooklyn, N. Y.

Application September 4, 1934, Serial No. 53,193

Term of patent 14 years

To all whom it may concern:

Be it known that I, Louis Davis, a citizen of the United States, and a resident of Brooklyn, in the county of Kings and State of New York, have invented a new, original, and ornamental Design for a Sleeping Garment or Similar Article, of which the following is a specification, reference being had to the accompanying drawing, forming part thereof, wherein:—

Fig. 1 is a view in rear elevation of a sleeping garment or similar article embodying my new design, and

Fig. 2 is a front elevational view thereof.

The distinctive feature of applicant's design resides in providing the upper portion of the garment at the rear with a yoke member having

at its top a scallop for the neck; at its bottom an apron-like panel with rounded lower corners, and defined by a seam which merges in curved lines at each side into the seam of each sleeve, the line of said seam being continuous from the extremity of one sleeve, across the back, and to the extremity of the other sleeve, said seam being at the lower edge of each sleeve, and springing from an intermediate portion of said panel substantially removed from the lower edge thereof.

I claim:—

The ornamental design for a sleeping garment or similar article as shown and described.

LOUIS DAVIS.
